Katherine McCrae, Inventor.

By Frank H. Drury Atty's.

UNITED STATES PATENT OFFICE.

KATHERINE McC LAIRE, OF CHICAGO, ILLINOIS.

CURLER.

1,397,532.

Specification of Letters Patent.

Patented Nov. 23, 1921.

Application filed June 8, 1921. Serial No. 476,081.

To all whom it may concern:

Be it known that I, KATHERINE McC LAIRE, a citizen of the United States, residing at Chicago, in the county of Cook and State 5 of Illinois, have invented new and useful Improvements in Curlers, of which the following is a full, clear, concise, and exact description, reference being had to the accompanying drawing, forming a part of this 10 specification.

My invention relates to improvements in curlers, and has for its object the production of a device that will retain its shape when used for the purpose for which it is intended, 15 and one that can be straightened readily after use.

A further object is the production of a device of simple construction, and one that is not liable to get out of order.

20 These and such other objects as may appear hereinafter are attained by my device, an embodiment of which is illustrated in the accompanying drawing, in which—

Figure 1 represents a perspective view of 25 my device;

Fig. 2 represents a sectional view of Fig. 1, and

Fig. 3 represents an enlarged view of the end portion of my device.

30 Like numerals of reference indicate like parts in the several figures of the drawing.

Referring now to the drawings—my device comprises a flexible fibrous tube or envelop, 4, within which is positioned a large 35 wire or rod 5, preferably of copper, completely filling the tube, the ends of the tube being confined, as shown at 6, to hold the rod in place. The fibrous envelop or tube is slightly longer than the rod, and the ends 40 secured preferably by a thread or string wound tightly around the ends and preferably sewed through the end, thus preventing any chance of the rod being withdrawn.

The copper rod is very soft grade, so as to 45 be very flexible and assume any shape to which it may be bent in using the device,

and so that it can be straightened out and made to assume its original position without danger of breaking.

Heretofore tubes have been employed with 50 a plurality of wires therein, but much difficulty has been experienced in the wires breaking and forcing the ends through the fiber envelop, or in the original ends of the wire coming through and scratching the 55 user. In the form in common use, it is difficult, often, to straighten the devices and pull them from the hair without either catching the hair or causing it to snarl. My device, however, can be pressed straight and 60 slipped out of the hair without difficulty or interference.

By the use of a single rod or large wire, all 65 this objection is eliminated, and an article of great use and value produced.

I am not limiting myself to copper, as there are other metals and materials having a proper degree of flexibility that will serve the purpose.

Having thus described my invention, I 70 claim—

1. A curler comprising a bar of soft copper of substantial size, circular in shape, a tube of flexible material surrounding said bar, the ends of said tube stitched together 75 and securely tied and said ends extending beyond the stitched portion.

2. A curler comprising an integral bar of soft copper of substantial size and circular in shape, a tube of flexible material with- 80 in which said bar is placed, the ends of said tube extending beyond the ends of said bar, thread being stitched through the ends of said tube adjacent to the ends of the bar, said thread being wound several times 85 around said tube and drawn tightly to prevent the removal of said bar, the ends of said tube being extended beyond said confined portion.

In witness whereof, I have hereunto sub- 90 scribed my name.

KATHERINE McC LAIRE.
